CLAIM

The ornamental design for a portable beverage dispenser with four spigots and two dividers, as shown and described.

DESCRIPTION

FIG. 1 is an exploded top perspective view of a portable beverage dispenser with four spigots and two dividers showing my new design;

FIG. 2 is an exploded side elevational view thereof (the opposite side elevation being a mirror image thereof);

FIG. 3 is an exploded front elevational view thereof (the rear elevation being a mirror image thereof);

FIG. 4 is an exploded top plan view thereof;

FIG. 5 is an exploded bottom plan view thereof;

FIG. 6 is an exploded top perspective view with the dividers inside;

FIG. 7 is an exploded top perspective view with the dividers removed and separated; and,

FIG. 8 is an exploded enlarged sectional view taken along line 8-8 of FIG. 6.
